(57) **CLAIM**

The ornamental design for a display screen with a graphical user interface, as shown and described.

DESCRIPTION

The sole FIGURE is a front view of a display screen with a graphical user interface showing the claimed design. The broken lines shown in the sole FIGURE show portions of the environment and form no part of the claimed design. The top right menu icon, the FIGURES within the top left circle, the text, the leaves, and all of the elements within the shoes are broken lines and form no part of the claimed design.
